UNITED STATES PATENT OFFICE.

CHARLES J. AULBACH, OF PASSAIC, NEW JERSEY, ASSIGNOR TO PASSAIC METAL WARE COMPANY, OF PASSAIC, NEW JERSEY, A CORPORATION OF NEW JERSEY.

SEALED CONTAINER.

Application filed May 29, 1925. Serial No. 33,650.

The object of my invention is to provide a container, such as an ordinary tin can, with a metal seal at one end which will be securely attached thereto to prevent the entrance of air and moisture and will serve to keep the container closed against surreptitious opening, and in which the seal may be readily removed.

In carrying out my invention I provide a sealing cover having a curved marginal portion to fit against an inwardly extending or curled edge portion of a container body at its open end, and I force the metal of said marginal portion of the sealing cover laterally and tuck it partially under said curled edge portion of the body, causing the material of said marginal portion to flow as required to be pressed under said curled edge and make a tight fit therewith, a portion of the margin resting upon said curled edge portion.

My invention also comprises novel details of improvement that will be more fully hereinafter set forth and then pointed out in the claims.

Reference is to be had to the accompanying drawings forming a part hereof, wherein—

Fig. 1 is a partly sectional side view of a container upon which the sealing cover is applied ready to be secured to the container;

Fig. 2 is a sectional view illustrating the sealing cover secured on the container; and

Figs. 3 and 4 are sectional views illustrating steps in the method of securing the container and its sealing cover together.

Similar numerals of reference indicate corresponding parts in the several views.

The container body 1 may be of any well known construction, such as customary in making so-called tin cans or sheet metal containers, provided with a bottom 2 which may be secured to the body by means of suitable seaming tools or by solder, or in any well known way. At the open end of the body, opposite the bottom 2, the metal at the edge is extended or curled inwardly forming a bead or rib at 3 serving to stiffen the mouth of the body and to cooperate with a sealing cover 4. The sealing cover 4 may be made of suitable thin metal and is provided with a curved marginal portion 5 that is adapted to fit against the curled edge 3 of body 1, as illustrated in

Fig. 1. The marginal portion 5 may be made by stamping a disk of metal in any desired way. By preference a rubber compound is applied against the inner curved surface of the marginal portion 5 of the sealing cover before the latter is applied upon the body 1 to assist in producing a tight sealing of the parts. The marginal portion 5 of the sealing cover is placed upon the curled end portion 3 of the body and the inner part of said portion 5 is forced laterally and partly under the curled edge 3 of the body, the metal of the seal flowing in such a manner as to force or tuck the metal tightly into engagement with the curled edge 3, throughout the extent of the portion 5, the outer part or edge of the marginal portions being drawn inwardly along the curled edge of body 1 and resting thereon. The sealed container is indicated in Fig. 2 with the sealing cover secured to the open end of the body.

Suitable means may be provided for pressing the marginal portion 5 of the sealing cover under and into engagement with the curled edge 3 of body 1. In Figs. 3 and 4 I have illustrated rollers 6 having suitable annularly curved end portions 6^a adapted to engage the metal of the sealing cover to force its marginal portion 5 into engagement with the curled edge 3 of body 1. The rollers 6 are pivotally supported upon rock arms 7, shown in bell-crank form, that are pivotally supported upon a head 9 which may be supported in any suitable manner. At 10 is a rod or plunger slidably guided in a bore 11 of head 9 and preferably kept from rotating by a key 12. The rod or plunger 10 is operatively connected with the arms 7 by means of a pin 13 carried by the rod or plunger and operative in slots 7^a in said arms, whereby when the plunger is pushed toward body 1 the arms 7 will be tilted to force the rollers 6 laterally for expanding the metal of marginal portion 5 of the sealing cover 4, and when the operation of the rod is reversed the rollers will be withdrawn from the sealing cover. In the operation of applying the sealing cover to the container body the parts will be assembled substantially as indicated in Fig. 3; rod or plunger 10 will be rotated and be pushed toward the body 1. During such rotation of rod or plunger 10 the rollers 6 will be forced laterally with their edges 6^b brought

into contact with the metal at the point where the cover and marginal portion 5 join, whereby the metal of such portion will be expanded and caused to flow to force or tuck part of such metal under the curl 3 of body 1 into close contact therewith, as illustrated in Fig. 3.

In accordance with my invention I am enabled to make a tight fit between the curled edge 3 of body 1 and the marginal portion 5 of the sealing cover, whereby the latter is retained from being pushed in or from being forced out from the body. Such sealing cover may be applied after the body has been charged with the desired contents. When it is desired to remove the sealing cover it is merely necessary to pry the same up by inserting therethrough a suitable tool, such as an ice pick or strong nail, whereby the seal will snap from the body without disturbing or hurting the latter in any way.

The body may be provided with a removable cover 14 particularly for use after the sealing cover has been removed, and to protect the sealing cover during transportation. In the example illustrated the cover 14 has a flange 15 provided with threads 16 adapted to cooperate with threads 17 on the container body, said threads being so related that they will cause the cover to be retained with a tight fit on the body. The outer edge of the sealing cover is located sufficiently close to the rim of the body 1 not to interfere with flange 15. The cover 14 may be applied by rotating it in one direction and may be removed by rotating it reversely. An indenture or depression 18 in cover 14 is adapted to fit within the inner surface of the curled edge 3 of the container body when the sealing cover has been removed, and such indenture will fit within the inner marginal portion 5 of seal 4. A slip cover or any

other form of detachable cover for the can body may be used if preferred.

My improvement permits the sealing of can bodies in such a way as to prevent surreptitious access to the contents; will preserve the contents from air and moisture, and helps stiffen the charged container.

Having now described my invention what I claim is:

1. A container having an open end and provided with a sealing cover at said end, said end of the container having an inwardly extending edge portion and the sealing cover having a marginal portion extending under said edge portion in engagement therewith and having the outer edge of the marginal portion resting upon and terminating at the edge portion of the container in a position to permit the sealing cover to be pried from the body by a tool forced through said cover and pressed against the adjacent edge of the sealing cover.

2. A container having an open end and provided with a sealing cover at said end, said end of the container having an inwardly extending edge portion and the sealing cover having a marginal portion extending under said edge portion in engagement therewith and having the outer edge of the marginal portion resting upon and terminating at the edge portion of the container, and a removable cover to fit over and against the marginal portion of the sealing cover and to fit against the open end of the body when the sealing cover is absent from the body, the removable cover having a flange to fit around the body unobstructed by the sealing cover, the body and said flange having cooperative means to retain the removable cover upon the sealing cover and upon the open end of the body when the sealing cover is absent therefrom.

CHARLES J. AULBACH.
